MATTED FABRIC AND PROCESS OF PRO-
DUCING SAME

Ella M. Lapham, Minneapolis, Minn.

Application November 15, 1937, Serial No. 174,583

4 Claims. (Cl. 112—1)

My invention provides an improved mat or matted material herein designated as a "matted fabric", this term being used in a sense to include materials such as rugs, mats, carpets, and 5 heavy cloth-like materials. The invention also involves a new method or process of producing the material.

The body of the matted fabric is made from closely compacted body-forming strips or ribbons which, in the process of making, are bent or reversely folded to form alternate or reversed pleats or folds. These body strips or ribbons may, in themselves, vary in character. The most common way of production thereof would be to 10 tear or cut on the bias old cloth or the like into strips of a width that is to represent the thickness of the matted fabric. Such cloth strips may be either cotton, wool, or a mixture of the two, although, of course, wool will produce the best 15 article. However, the body strips may be produced in other ways, such, for example, as closely winding yarn into ribbon form and connecting the yarn by stitches or the like.

Regardless of the way that the body strips or 20 ribbons are produced or the character thereof, these pleated body strips are, in accordance with my invention, united by a stitching thread which, in a novel way, is stitched and looped through the folds of the ribbons at intermediate 25 portions of the loops, that is, about midway between the upper and lower surface-forming edges of the strips so that the warp thread firmly binds together the loops of the strips and the rows of strips with the warp thread embedded in the 30 fabricated body and protected against wear and invisible in the completed article.

The invention is illustrated in the accompanying drawings wherein like characters indicate like parts throughout the several views.

40 Referring to the drawings:

Fig. 1 is a fragmentary horizontal section taken approximately on the line 1—1 of Fig. 2, illustrating the manner in which the matted fabric is produced;

45 Fig. 2 is a section taken on the line 2—2 of Fig. 1;

Fig. 3 is a fragmentary section illustrating the first step in the manufacture of the article;

Fig. 4 is a perspective showing the manually- 50 operated needle used in the production of the article;

Fig. 5 is a section taken approximately on the line 5—5 of Fig. 1, but showing the pleats of the fabric drawn together as in the completed 55 article;

Fig. 6 is a view corresponding to Fig. 5 but showing a matted fabric of much less thickness than that illustrated in Fig. 5;

Fig. 7 is a view corresponding to Fig. 1 but illustrating a different way in which the warp 5 thread is interlooped in the production of the fabric;

Fig. 8 is a view partly in plan and partly in horizontal section illustrating the way of producing a body-forming ribbon out of yarn by 10 stitching through intermediate portions of the loops of the yarn;

Fig. 9 is a view much like that shown in Fig. 8, but showing an additional binding strip stitched 15 to the yarn; and

Fig. 10 is a perspective showing a section of the completed ribbon, also illustrated in Fig. 9.

Referring first to the construction illustrated in Figs. 1, 2, 3 and 5, the numeral 11 indicates the manually-operated needle used in the carrying out of the process in the production of the improved article. This needle 11 has an eye 12 through which is passed a thread 13, shown as knotted at one end, as indicated at 14. This thread may be ordinary thread, but usually will 20 be either a very heavy sewing thread or a still heavier material, such as cord or twine.

Referring now particularly to Fig. 1, the body of the matted fabric is made up of a multiplicity of body-forming strips or ribbons, only two of 30 which are shown, the first row being indicated as an entirety by the character A and the second row being indicated as an entirety by the character B. In the process of manufacture the ribbons A and B are bent to form alternate pleats 35 and, for illustrative purposes, the upwardly projected pleats of strip A are indicated by the character a, and the downwardly projected pleats of the strip by the character a'; while the upwardly projected pleats of strip B are indicated by the character b, while the downwardly projected pleats thereof are indicated by the character b'. The thread 13 threaded through the needle, as shown in Fig. 4, is in the operation 40 graphically illustrated in Fig. 1, applied as follows: The first pleat a is formed in the strip A and the thread, by use of the needle, is threaded through this first pleat to form the first thread loop 1a, and is then drawn back, carried over 45 the crown of the first pleat a to form a loop 1b and is then brought down through loop 1a and threaded through the second pleat a to form the second loop 1a, and is then brought back through 50 the first loop 1a and then is carried over the second 55

pleat *a* to form the second loop *1b* and from thence brought through the second loop *1a*.

This operation is continued throughout the pleats of the first strip A until the last pleat has been threaded. Then, by the use of the needle, the thread *13* is threaded through the first side of the first pleat *b* is looped downward at *1c* through the last loop *1b*, and is thence brought upward and threaded through the second side of the first pleat *b* to form a loop *1d*. Thence the thread is drawn backward and looped at *1b* over the crown of the first pleat *b* and from thence is passed downward through loop *1d*. From there on, the operation just described, in the application of the thread to the second strip B, is carried out or continued, as clearly indicated in Fig. 1.

It will be understood that the forming of the pleats in the strips will be progressive as the threading operation continues and that the thread will be progressively drawn taut to compact the pleats of the body-forming strips or ribbons. Of course, at the completion of the last stitching operation, the end of the thread will be secured against unwinding by tying, knotting, or any other suitable way. As illustrated in Figs. 2, 5 and 6, the thread is well protected at the intermediate portion of the body of the matted fabric and is entirely invisible.

The body-forming ribbons or strips will usually be strips cut from old cloth, the best for the purpose being woolen cloth or cloth largely wool. However, Figs. 8, 9 and 10 illustrate different or other ways of making up the body-forming ribbons or strips. As illustrated in Fig. 8, the yarn *15* is wound around the prongs of a wire fork *16* or the like and the loops of the yarn are united by stitches *17* produced either by hand or with a machine. After the strips have been formed, they may be pulled off from the fork *16* and the yarn cut at the outer edges either before or after it is removed from the fork.

Fig. 9 shows a reinforcing ribbon or tape *18*, preferably of cloth, applied to the loops of the yarn by the stitches *17*. Fig. 10 shows the completed article made as illustrated in Fig. 9 but removed from the fork.

The needle used for the above purpose is preferably curved from the eye *12* to its point which greatly facilitates the passing of the thread through the various loops and through the pleats or folds of the body-forming strips. In the use of this needle the thread is not, in the operation described, removed from the eye of the needle,

but is progressively moved through the folds or pleats of the body material and through the loops of the warp thread.

The structure illustrated in Fig. 7 is like that illustrated in Fig. 1 except that the thread from the second row is brought down not only through the crown forming thread loops of the first row, but is also passed downward at *C* and through the intermediate loops of the first row. In both of the structures described, the stitching is made by a single common thread that is interlocked with itself and without the use of a second thread.

In actual practice the weaving or making of the matted fabric, whether in the form of a rug or of other form, may be very rapidly accomplished.

What I claim is:

1. A matted fabric made up of rows of alternately pleated body-forming strips, and a single common thread threaded through the pleats of said strips intermediate of the edges thereof and interlooped between pleats, thereby interlocking the several rows of pleated body-forming strips.

2. A matted fabric made up of a multiplicity of pleated body-forming strips, and a single common thread passed through the pleats of said strips, said thread being interlooped between the pleats of individual strips and also interlooped and interlocked between the rows of body-forming strips.

3. A matted fabric made up of a multiplicity of rows of pleated body-forming strips and a single common thread passed through the loops of the adjacent pleated strips, the thread being interlooped between the pleats of each strip and the thread of the adjacent rows being interlooped and interlocked.

4. The process of producing a matted fabric which consists in pleating body-forming strips, in successively passing a thread through the pleats of the strips to form intermediate loops and from thence back through the pleat and intermediate loop and over the crown thereof, and from thence in the same manner through successive pleats, in passing the thread through the first wall of the adjacent body-forming strips, from thence downward and through loops of the first row, from thence through the second wall of the first pleat of the second row to form an intermediate loop, from thence backward and over the crown of the first pleat of the second row, and from thence through the first intermediate loop of the second row and repeating said operation in successive pleats of the second row.

ELLA M. LAPHAM.
